UNITED STATES PATENT OFFICE.

WILLIAM MARKOWITZ, OF CLEVELAND, OHIO.

COMBINED BRUSH AND COMB.

• 1,287,383.

Specification of Letters Patent. Patented Dec. 10, 1918.

Application filed January 2, 1918. Serial No. 210,037.

To all whom it may concern:

Be it known that I, WILLIAM MARKOWITZ, a citizen of the United States, resident of Cleveland, county of Cuyahoga, and State of Ohio, have invented certain new and useful Improvements in Combined Brushes and Combs, of which the following is a specification.

This invention relates to improvements in combined brushes and combs, in which a comb is engaged with the brush backing.

The principal object of the invention is to provide a brush with a comb at its edge convenient for use, a further object is to form a brush backing in which is pivotally secured a comb, and means by which the comb can be extended or retracted when desired.

These and other like objects are attained by the novel construction and combination of parts hereinafter described and shown in the accompanying drawing, forming a material part of this disclosure, and in which—

Figure 1 is a perspective view, looking from the back or upper side of a brush, made in accordance with the invention.

Fig. 2 is a plan view showing a modification of the same, the comb being shown in full lines as in a folded position and by broken lines as extended for use.

Fig. 3 is a transverse sectional view taken on line 3—3 of Fig. 1.

Fig. 4 is a transverse sectional view taken on line 4—4 of Fig. 2, and

Fig. 5 is a fragmental sectional view taken on line 5—5 of Fig. 2.

The invention is comprised of a solid brush backing 10 combined with a handle 11, upon one side of which is engaged tufts of bristles 12, in all respects as in the manner in which brushes are at present made.

In Fig. 1 is shown an ordinary form of oval brush in which one row of the bristle tufts 12 is omitted and in place thereof is the curved back 14 of a comb, the teeth 15 of which are preferably extended at some distance below the bottom of the bristles so that they may be used in an ordinary manner, the brush backing having a recess in its back for the comb which is rigidly fixed therein.

In Figs. 2, 4 and 5, there is formed in the upper side of the backing 10 a longitudinal recess 18, containing a comb 20, having teeth 21, the back of the comb having a pin 23, at one end engaging in an appropriate opening formed in the end wall of the recess 18, while at the opposite end of the comb is a stem 24, bent outward into a crank 25 and pivotally connected with the end of a rod 26 having a knob or head 27 at its opposite end, the same being normally seated in a transverse recess 28, formed across the back of the brush, a recess 30 being provided for the knob, while the crank 25 and end of the rod 26 operate in a recess 31 adjacent to the end of the comb, a clip 32 holding the rod in operative position in its recess.

When it is desired to use the comb the extending knob 27 is pulled outwardly, operating the crank, and turning the comb upon its pivots so that the same is extended parallel with the edge of the brush permitting the comb to be used in an ordinary manner.

If the device is used as a brush, the knob 27 is pressed into the recess 30 whereby the comb is folded into the recess 18 in an obvious manner.

Having thus described my invention, what I claim as new and desire to secure by Letters Patent, is—

In a combination brush and comb, a backing, a transverse recess and a depression in said backing, a comb, pins at its back for pivotally securing said comb to said brush backing to fold into the depression of the same, a crank at one of the pivot pins of said comb, and a rod pivotally connected to said crank and located in the transverse recess of said backing, a knob at the opposite end of said rod, adapted to be pressed into the transverse recess, and a clip for holding the rod in operative position in said transverse recess, substantially as described, and for the purpose set forth.

In testimony whereof I have affixed my signature.

WILLIAM MARKOWITZ
